UNITED STATES PATENT OFFICE.

CALVIN B. DEYO AND ALONZO G. CARMAN, OF MARENGO, ILLINOIS.

UNIVERSAL JOINT.

SPECIFICATION forming part of Letters Patent No. 267,844, dated November 21, 1882.

Application filed September 28, 1882. (No model.)

To all whom it may concern:

Be it known that we, CALVIN B. DEYO and ALONZO G. CARMAN, citizens of the United States of America, residing at Marengo, in the county of McHenry and State of Illinois, have invented certain new and useful Improvements in Universal Joints; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in shaft-couplings, and it is designed more especially to be used in connection with wind-wheels or similar powers in which it is desirable to convert the motion from a horizontal rotary shaft to a vertical rotary shaft, which shafts are journaled at right angles with each other in a frame; and our invention consists of a gimbal or universal joint of peculiar construction, as will be hereinafter set forth, when used in combination with a rigid frame having a central opening and shaft-bearings at right angles with each other, as will be hereinafter more fully set forth, and pointed out in the claims.

In the annexed drawings, Figure 1, we have shown our invention in connection with a solid frame or rotary support for a wind-engine; and Fig. 2 is a view showing a joint and coupling-rod with the frame removed.

A on the annexed drawings represents a frame or casting, which is provided at one end with a means or projection for attaching the vane, and on its opposite side with the shaft-bearing through which passes the shaft to which the wind-engine is attached. This casting is provided on its lower side with a tapering journal, which rests within and on suitable bearings attached to the supporting-frame or roller-table. This tapered bearing and the vertical shaft-socket are located at right angles with the bearing and shaft which support the wind-wheel. The casting A is provided with a central opening of a sufficient size to receive the connecting means for the ends of the shaft. The ends of the horizontal and vertical shafts B and C within the casting A are

provided with yokes a a, having shaft-sockets at one end, the end portion of these yokes being bifurcated, which members b b diverge from each other, so as to form an angle above the shaft-socket of about forty-five degrees. The ends of these members b b are provided with journals b' b', which are formed on the ends of the same, so as to be at right angles with the shaft to which they are attached. They are also provided with shoulders c c at right angles with the journals b' b'. Each of these yokes a a is provided with rings D D', having at opposite sides sockets, in which rest the journals b b, the shoulders c c bearing upon the inner rims of these rings. The intermediate or connecting portion of this coupling consists of a joint, E, having a straight central portion, e, from which diverge arms or members d d and d' d'. These arms or members project from the central portion, e, of the connecting means E, so as to fit within the rings D D'. The members or arms which are attached to the central portion, e, are also formed so as to extend in opposite directions or at right angles to each other, and they are journaled within the rings D D' opposite the arms b b. The ends of the members d d' are provided with journals and shoulders similar to those formed on the end of the members b b.

The parts of this coupling or gimbal joint are secured to each other by the rings D D', which are provided with four openings or perforations at equal distances from each other. These rings are secured to the journals on the end of the members by heating the same until they have expanded sufficiently to allow the journals to be placed in their respective sockets. By this means the parts are united securely to each other.

We are aware that universal joints have heretofore been constructed having a central portion connected to the ends of the coupling-rods by crosses having arms on the same plane, and that a single ring has also been employed to connect the parts; and we do not claim such as our invention, which is designed to obviate the vibratory and unsteady motion which accompanies the usual form of universal joints, and renders them objectionable. Securing the rods within a rigid frame, as described, also increases the steadiness of the motion.

Having thus described our invention, what we claim as new, and desire to secure by Letters Patent, is—

1. The frame A, having shaft-bearings at right angles with each other and the central opening, in combination with a horizontal and vertical shaft having coupling means consisting of the yokes *a a*, having members *bb*, rings *D D'*, and central member, E, with arms at right angles with each other, substantially as shown, and for the purpose set forth.

2. A universal coupling for the purpose set forth, consisting of the yokes *aa*, having means for attaching the same to the ends of shafts, and projecting members *b*, having on their

ends journals *b'* and shoulders *c*, and intermediate member, E, having straight portion *e*, the members projecting at right angles with the portion *E*, the parts being connected to each other by rings *D D'*, which embrace the ends of the members, substantially as shown and described. 20

In testimony whereof we affix our signatures in presence of two witnesses.

CALVIN B. DEYO.
ALONZO G. CARMAN.
